WALL TILE ATTACHMENT

Andrew W. Nelson, Terre Haute, Ind., assignor
to Columbian Enameling & Stamping Co.,
Terre Haute, Ind., a Corporation of Indiana

Application October 8, 1931. Serial No. 567,651

6 Claims. (Cl. 189—85)

My invention relates to wall tile attachment and more particularly to the provision of means whereby metal tile can be properly provided with corners to make a smooth rounded corner for the vertical corners of a room in which the tile is used.

It is the principal purpose of this invention to provide an improved metal tile corner construction by means of which the corners may be closed by special corner tiling that makes a smooth joint with the usual wall tile.

I will describe the preferred form of my invention by reference to the accompanying drawings wherein—

15 Fig. 1 is a perspective showing a protruding or external corner which is covered by the improved corner tile of this invention;

Fig. 2 is a similar view illustrating the internal corner construction;

20 Fig. 3 is a section substantially on the line 3—3 of Fig. 1;

Fig. 4 is a section substantially on the line 4—4 of Fig. 2;

25 Fig. 5 is a perspective view of a base corner tile;

Fig. 6 is a perspective view of an intermediate unit;

Fig. 7 illustrates the top internal corner tile in perspective.

30 Fig. 8 is a similar view of a bottom internal corner tile; and

Fig. 9 is a section substantially on the line 9—9 of Fig. 8.

35 Referring now in detail to the drawings, it is to be understood that the tile referred to herein preferably are made of sheet metal enamel to provide a smooth outer surface which can be readily cleaned and kept in good condition. Owing to the fact that the enamel is easily chipped considerable care is necessary in mounting these tiles, and it is essential that proper provision be provided to prevent the formation of sharp exposed corners as they would naturally be most quickly injured in the normal life of a tile. The corner tile in the present invention can readily be applied in conjunction with the wall tile to make a smooth-fitting tile wall leaving no exposed sharp corners.

40 Referring now to Figs. 1 and 2, the back wall 10 has what I term a clip board 11 secured thereto in any suitable manner as by nailing and this clip board carries rows of clips 12 which clips are adapted to engage the flanges 13 and 14, for example, of a flat wall tile so as to reasonably hold the tile in place. In order to ob-

tain good smooth joints, it is necessary that the tile be flanged on all four edges, and of course, when the corner is reached, difficulty is encountered in making the corners match without leaving an exposed edge or an opening. 60

Before describing the method of overcoming this difficulty, I wish to point out the manner in which the top and bottom tile of the wall sections fit in with the floor and the vertical wall above the tile. 65

The tile floor 15 is made to join smoothly with the wall tile by curving the wall tile outwardly as shown at 16 and providing a depending flange 17 which is substantially the depth necessary to apply the floor tile. Now in connection with the 70 top or cap tile, this tile is preferably turned in as shown at 18 and then provided with the depending flange or shoulder 19 which is spaced from the plane of the main portion of the tile a distance such that it will engage the rough 75 plaster at 20 against which the wall board or clip board 11 is secured. The smooth or finishing plaster at 21, therefore, extends a trifle over the shoulder of the tile so as to make a good 80 fitting joint at this point.

In order to illustrate the manner of covering an external corner, I will refer to Figs. 1, 3, 5, and 6 illustrating this structure.

The bottom corner tile 22, the intermediate 85 tile 23, and the top tile 24 are the three shapes necessary for this construction. In addition an extra mounting strip or clip must be provided for the corner.

This clip is illustrated in section at 25 and is 90 preferably nailed to the abutting clip boards 11, as illustrated, these boards of course being fastened so that the corners can not open or spread. I might say that the usual size in which the clip board is made is in blocks 28 inches wide and 44 inches high although these dimensions may vary. 95 The mounting strip 25 may run from the floor up to near the top of the cap tile or may be in small broken sections if desired. Preferably, however, it is made of a single strip running the full depth of the tile wall.

100 The corner tile itself has the bowed portion curved to substantially a quadrant of a circle and then has the flanges 27 and 28 at the side edges turned inwardly toward each other at an angle of 90 degrees, and these side flanges engage the flanges 29 and 30 of the mounting strip 25. The bottom of the base corner piece 22 is spread out as indicated at 31 and 32 so as to have substantially the same curvature as the 105 portion 16 of the adjacent base wall tile. Thus a 110

smooth corner is effected at the base. The top of the base tile 22 has a smaller flange 33 turned in upon which the tile 23 may rest. This flange 33 must necessarily be of less depth than the 5 side flanges 27 and 28 in order to pass over the corner to be covered, and also the ends at 34 and 35 must terminate short of the flanges 27 and 28 preferably just such a distance as to receive the flanges 29 and 30 upon the mounting strip.

10 Any necessary number of intermediate tile 23 can be provided depending upon the height of the wall tile and the length of the intermediate corner tile elements.

The corner tile are assembled by sliding them 15 over the retaining flanges on the mounting strip.

Cap corner tile 24 is exactly the same as the intermediate tile 23 with the exception that the sides are curved in as indicated at 36 and 37 so that they come together at right angles, their 20 flanges 27 and 28 being joined so as to form a smooth surface to be abutted by the side flanges on the cap wall tile.

Now with respect to the internal corners such 25 as shown in Figs. 2 and 4 and 7 to 9, the curve in the corner tile must now be inward as illustrated at 38 on Fig. 4. The mounting strip 39 fits tightly in the corner between the wall boards 11 and is nailed thereto in a suitable manner. Like corner strip 25, this strip may also be divided into sections but preferably it is made in 30 one piece for the height of the tile wall. With this corner piece, however, the edges 40 and 41 instead of being bent at right angles are merely raised to provide a slot between them and the wall boards 11. The corner tile are then provided 35 with the shoulders at 42 and 43 for abutting the side edges of the adjacent wall tile and are again turned to form the flanges 44 and 45 which slide beneath the raised portions 40 and 40 41 to anchor the corner tile in place.

The bottom tile 46, as shown most clearly by 45 Figs. 2, 4, and 8, has the side edges 42 and 43 running right down to the tip of the outwardly bent portion 47 but the flanges 44 and 45 terminate at the top of the outwardly bent portion 47 as otherwise they could not slide behind the strip for interlocking purposes.

The intermediate tile and the top portion of 50 the bottom tile 46 are preferably flanged in the same manner at the ends as are the external corner tile as indicated at 33 leaving merely enough space between the securing flanges 44 and 45 on the end flange for the edges 40 and 41.

55 The cap corner tile for an internal corner is shown in perspective at 48 in Fig. 7, and the external appearance is illustrated more clearly in Fig. 2. The side flanges 44 and 45 are again terminated short of the cap portions 49, but shoulders 42 and 43 continue right up to the cap 60 49 which has the downturned flange 50 abutting against the wall proper.

Thus it will be seen that these tile can be applied in substantially the same manner as described with the external corner tile making a smooth unbroken joint with suitable bearing surfaces provided to abut against the flanges of the adjacent wall tile and with no sharp edges left exposed to become chipped or broken.

70 From the above description, it is believed that the construction and advantages of this device will be clear to those skilled in this art.

Having thus described one form of my invention, what I claim as new and desire to secure by Letters Patent is:

1. A corner structure for mounting sheet metal, wall tile at the meeting of two walls comprising a securing strip anchored to both the walls adjacent the corner thereby tying the walls together and having side flanges standing out from said walls and directed angularly away from each other, and corner tile members having side flanges directed angularly toward each other slidably receiving the side flanges of said strip therebetween said tile members having end flanges at their abutting ends which end flanges terminate short of the side flanges thereon providing passage for the side flanges of the securing member between the end flanges and side flange of a tile member.

80 15 2. A corner structure for mounting sheet metal wall tile at the meeting of two walls comprising a securing strip anchored to both the walls adjacent the corner thereby tying the walls together and having side flanges standing out from said walls and directed angularly away from each other, and corner tile members having side flanges directed angularly toward each other slidably receiving the side flanges of said strip therebetween said tile members having end flanges at their abutting ends which end flanges terminate short of the side flanges thereon providing passage for the side flanges of the securing member between the end flanges and side flange of a tile member.

- prising a securing strip anchored to both the walls adjacent the corner thereby tying the walls together and having side flanges standing out from said walls and directed angularly away from each other, and corner tile members having side flanges directed angularly toward each other slidably receiving the side flanges of said strip therebetween said tile members having end flanges at their abutting ends which end flanges 5 terminate short of the side flanges thereon providing passage for the side flanges at the securing member between the end flanges and side flange of a tile member, said tile members having longitudinal shoulders disposed substantially 10 at right angles to said side flanges for abutting adjacent wall tile, the bottom tile having its lower end and the shoulders thereon curved outwardly away from the wall with the shoulders converging toward the end.
- 15 6. A corner structure for mounting sheet metal wall tile at the meeting of two walls comprising a securing strip anchored to both the walls adjacent the corner thereby tying the walls together and having side flanges standing out from said walls and directed angularly away from each other, and corner tile members having side flanges directed angularly toward each other slidably receiving the side flanges of said strip therebetween said tile members having end flanges at their abutting ends which end flanges 20 terminate short of the side flanges thereon providing passage for the side flanges of the securing member between the end flanges and side flange of a tile member, said tile members having longitudinal shoulders disposed substantially at right angles to said side flanges for abutting adjacent wall tile, the side flanges on the top and bottom tile terminating short of the top and bottom ends respectively thereof.
